(57) **CLAIM**

The ornamental design for a plant support, as shown and described.

DESCRIPTION

1. Plant support

1.1 : Perspective

1.2 : Perspective

1.3 : Perspective

1.4 : Bottom

1.5 : Top

Design 1 relates to the outer appearance of arch-shaped plant support, like a tomato truss support and, is characterized by honeycomb-shaped spine segments merging into downward projecting legs and S-shaped outer end lips.
